(57) **CLAIM**

The ornamental design for a wear cap for a corner adapter of an excavator bucket tooth, as shown and described.

DESCRIPTION

1. Wear cap for a corner adapter of an excavator bucket tooth

1.1 : Front perspective view

1.2 : Right

1.3 : Left

1.4 : Front

1.5 : Back

1.6 : Top

1.7 : Bottom

1.8 : Back perspective view

Figure 1.1 is a front perspective view of the wear cap; Figure 1.2 is a right view of the wear cap; Figure 1.3 is left view of the wear cap; Figure 1.4 is a front view of the wear cap; Figure 1.5 is a back view of the wear cap; Figure 1.6 is a top view of the wear cap; Figure 1.7 is a bottom view of the wear cap; Figure 1.8 is a back perspective view of the wear cap; the broken lines in the reproductions illustrate portions of the wear cap which form no part of the claimed design.

1 Claim, 8 Drawing Sheets
